THREADING TOOL

Harding F. Bakewell, San Marino, Calif.

Application February 7, 1940, Serial No. 317,687

9 Claims. (Cl. 10—141)

This invention is a threading tool, either a tap having an exterior cutting-thread for internally threading the work or a die having an interior cutting-thread for externally threading the work.

It is an object of the invention to interrupt the circumference of the cutting-thread by longitudinal flutes of appreciably greater number than heretofore employed. More particularly, it is an object of the invention to provide longitudinal flutes on the order of approximately twelve or more per circumference.

It is a further object of the invention to provide longitudinal flutes of a width circumferentially of the cutting-thread approximately equal to arcuate lengths of the cutting-thread between next adjacent flutes.

More particularly, it is an object of the invention to provide longitudinal flutes on the order of approximately twelve or more per circumference, with approximately equal width of the flutes and arcuate length of the cutting-thread between next adjacent flutes.

It is a still further object of the invention to adapt the cutting-thread for reversal for use of either end of the cutting-thread.

More particularly, it is an object of the invention to provide a cutting-edge and a relieved-edge for each arcuate length of the cutting-thread which is between next adjacent flutes, with that portion of the cutting-thread which is between one of its ends and medially of its length having its cutting-edges and its relieved-edges reversed with relation to the cutting-edges and the relieved-edges of that portion of the cutting-thread which extends from medially of its length to its opposite end.

It is a still further object of the invention to adapt the cutting-thread for readily detachable mounting on a tool shank which is in turn adapted for mounting in any usual holder; the detachable cutting-thread, in the case of a tap, comprising an annulus having an exterior tapping thread and adapted for reception of the annulus on the tool shank, and in the case of a die, comprising an annulus adapted for reception of an internally threaded die in one end thereof and adapted for reception of its other end on the tool shank.

It is a still further object of the invention to provide a longitudinally floating mounting for the thread-cutting unit on the tool shank.

More particularly, it is an object of the invention to mount the thread-cutting unit on the tool shank for longitudinal displacement relative

thereto, with the thread-cutting unit fixed against rotation relative to the tool shank when longitudinally displaced responsive to pressure exerted by thread-cutting engagement with the work; and with the thread-cutting unit, when longitudinally displaced in the opposite direction, adapted for free rotation relative to the tool shank in the direction of thread-cutting relative rotation of the tool and the work, but fixed against rotation relative to the tool shank in the opposite direction.

Further objects of the invention will be readily understood from the following description of the accompanying drawing which illustrates various forms which the invention may assume in practice, it being understood that the forms which are shown and described are for the purpose of illustration and that the invention may be modified and is entitled to various forms without departing from the scope of the appended claims.

In the drawing:

Fig. 1 is a side elevation of the invention as embodied in a tap, showing conventional mounting for the shank of the tap.

Fig. 2 is an enlarged side elevation of the tap and its shank, partly in axial section.

Fig. 3 is a transverse section on the line 3—3 of Fig. 2.

Fig. 4 is a side elevation of the invention as embodied in a die, with the thread-cutting unit in axial section.

As embodied in a tap, the cutting-thread is an exterior thread 1 on an annulus 2, with the circumference of the cutting-thread interrupted by longitudinal flutes 3. A relatively large number of flutes are provided, as distinguished from prior practice of employing flutes on the order of four to six per circumference, the number of flutes being on the order of approximately twelve or more per circumference. The flutes are equidistantly spaced, forming uniform arcuate lengths of the cutting-thread between next adjacent flutes. The flutes, instead of being of relatively narrow width compared with the length of the interrupted arcs of the cutting-thread, are preferably of approximately the same width as the length of these interrupted arcs.

In the direction of thread-cutting relative rotation of the tool and the work (indicated by arrow A) the leading edges of the arcs of the cutting-thread are preferably undercut so as to form cutting-edges 4, and the trailing edges of the arcs of the cutting-thread are preferably chamfered so as to form relieved-edges 5. At the end of the tool which initially engages the work

the thread 1 is preferably chamfered as shown at 6 for starting the thread-cutting operation.

By the construction as thus described, a relatively large number of cutting-edges 4 are adapted for cutting engagement with the work at each rotation of the tool relative to the work, as is particularly advantageous when the chamfer 6 is comparatively short so that the full cutting diameter of the thread 1 is attained before many relative rotations of the tool have been made, the improved construction providing for appreciably increasing the number of cutting engagements at edges 4 by the time full cutting diameter is reached. Furthermore, the cutting-thread clears the work a relatively large number of times during each rotation of the tool relative to the work, i. e. at each of the flutes 3, thereby adapting the tool for thread-cutting with each arcuate length of the cutting-thread concentric with the axis of rotation throughout its entire length from its leading to its trailing edge as indicated at 7, instead of necessitating each arcuate length being relieved from true concentricity toward its trailing edge.

For convenient and economical replacement of the cutting thread when it becomes worn, the annulus 2 is adapted for reversal on the tool shank and the thread 1 extends the length of the annulus for thread-cutting engagement with the work irrespective of which end of the thread is the leading end. For this purpose, one side of each of the flutes 3 has cutting-edges 4 in longitudinal alignment along the same, from the chamfered end 6 to medially of the length of the thread 1, and has relieved-edges 105 (similar to the edges 5 previously described) in longitudinal alignment along the same from medially of the length of the thread to its opposite end. In similar manner, the other side of each of the flutes 3 has relieved-edges 5 in longitudinal alignment along the same, from the chamfered end 6 to medially of the length of the thread 1, and has cutting-edges 104 (similar to the edges 4 previously described) in longitudinal alignment along the same from medially of the length of the thread to its opposite end. The end of the thread which is opposite its chamfered end 6, is similarly chamfered as shown at 106.

The thread-cutting annulus 2 is adapted for mounting on a shank 10 which is in turn adapted for mounting in any usual holder, e. g. a chuck, turret head, etc. For purpose of illustration, the shank 10 is shown fixed against rotation in a turret head 11 for thread-cutting relative rotation of the tool and the work by rotating the work (not shown), with the tool and the work adapted for relative axial feed by axial displacement of either the turret head or the work.

The thread-cutting annulus 2 is mounted on the shank 10 for ready reversal for use of either end of the thread 1, and is adapted for longitudinal displacement relative to the shank 10 with its longitudinal displacement limited in that direction in which pressure is exerted against the annulus responsive to its thread-cutting engagement with the work. For this purpose, the shank 10 is shouldered as shown at 12, and the bore 20 of the annulus 2 is adapted for journaled sliding reception on the reduced bearing-end 13 of the shank.

When the annulus 2 is longitudinally displaced on its bearing 13 so that it is adjacent or abutting the shoulder 12, it is fixed against rotation relative to the shank 10. For this purpose, pins

14 may project from the shoulder 12 longitudinally of the shank 10, for reception in cooperating bores 15 or 115 which are provided in the respective ends of the annulus 2. The thread-cutting annulus may thus be readily slipped onto the end 13 of the shank 10 so as to engage the shoulder 12, with the pins 14 received in their cooperating bores and locking the annulus against rotation relative to the tool shank, and with either end of the thread 1 positioned for thread-cutting engagement with the work.

When the annulus 2 is longitudinally displaced on its bearing 13 so as to no longer abut the shoulder 12, it remains fixed against rotation relative to the tool shank as long as the pins 14 are received in the bores 15 or 115, but this locking engagement is released as soon as relative longitudinal displacement of the annulus 2 shifts it clear of the pins 14. The annulus 2 is then free for rotation on its bearing 13 in the direction (indicated by arrow A) of thread-cutting relative rotation of the tool and the work; but means are provided for locking the annulus 2 against rotation on its bearing 13 while permitting free longitudinal displacement relative thereto, when the direction of relative rotation of the tool and the work is opposite to that indicated by arrow A, i. e. in the direction for thread-cutting withdrawal of the tool from the work.

As an instance, a one-way clutch is provided between the bearing 13 and the bore 20 of the annulus 2, adapted for automatic engagement when the direction of relative rotation of the tool and the work is opposite that indicated by arrow A, and adapted for automatic disengagement when the direction of relative rotation is as indicated by arrow A. The clutch may comprise a roller 16 journaled in a groove in the periphery of the bearing 13 and held against radial displacement from its groove as shown at 18. The roller is adapted for lateral play in its groove, with the base of the groove inclined as shown at 19.

When relative rotation of the annulus 2 and the shank 10 is in the direction indicated by arrow A, frictional contact of the roller 16 with the bore of the annulus laterally shifts the roller in its groove to the deep side of the groove, in which position the periphery of the roller is clear of the bore of the annulus, thereby permitting free relative rotation of the annulus and the tool shank. When relative rotation of the annulus 2 and the shank 10 is in the direction opposite to that indicated by arrow A, frictional contact of the roller 16 with the bore of the annulus laterally shifts the roller in its groove to the shallow side of the groove, in which position the periphery of the roller projects beyond the periphery of the bearing 13 for binding engagement with the bore of the annulus, thereby fixing the annulus against rotation relative to the tool shank.

In operation, with the annulus 2 mounted on the bearing 13 against the shoulder 12 so that the pins 14 fix the annulus against rotation relative to the tool shank, and with the work and the tool shank relatively rotated in thread-cutting direction as indicated by arrow A, relative axial feed of the tool shank toward the work axially feeds the annulus 2 for threading the work by the relatively rotating thread 1; and as soon as the thread has been started, its threaded engagement with the relatively rotating annulus 2 maintains thread-lead of the annulus for continuing the thread-cutting operation. In other words,

the thread of the annulus 2 is adapted to thread the work by floating thread-lead of the annulus relative to the shank 10, responsive to its threaded engagement with the thread which has been cut, and free of positive feed of the shank 10 as long as feed of the tool shank is sufficient to prevent such relative longitudinal displacement of the thread-cutting annulus as would release it for relative rotation by clearing it of the projecting pins 14.

When relative axial feed of the shank 10 toward the work is arrested, threaded engagement of the annulus 2 with the thread which has been cut, thus continues the threading operation until longitudinal displacement of the annulus 2 relative to the tool shank 10 clears it of the pins 14, whereupon the annulus 2 is free for rotation relative to the tool shank and will thus rotate with the threaded work, thereby arresting the threading operation irrespective of continued relative rotation of the tool shank and the work.

When the tool shank and the work are then relatively rotated in the opposite direction, the roller 16 fixes the annulus 2 against rotation relative to its bearing 13 while leaving the annulus free for longitudinal displacement relative to said bearing. The annulus 2 and the work are thus relatively rotated in the direction opposite to that indicated by arrow A, for threaded retraction of the annulus from the work by its threaded engagement with the thread which has been cut. In other words, while being retracted from the work the annulus 2 is adapted for floating thread-lead relative to the shank 10, responsive to its threaded engagement with the threaded work, and free of positive retractive feed of the shank 10, the retractive feed of the tool shank being employed merely for clearing its shoulder 12 of the annulus 2 during threaded retraction of the annulus from the work.

The annulus 2 is of relatively light material such as an aluminum alloy, and since it is free floating relative to its shank 10 while threading the work and during retraction from the threaded work, the longitudinal pressure against the cut thread is merely that resulting from thread-lead of this relatively light annulus, exclusive of the weight of the relatively heavy tool shank 10, thereby threading the work without distorting the cut thread.

As embodied in a die for externally threading the work (as illustrated at Fig. 4), the construction is the same as previously described except that the cutting-thread is formed in the bore of an auxiliary annulus which is detachably mounted in the bore of the annulus which is adapted for free floating mounting on the tool shank, similar parts being indicated by the same reference numeral with the exponent a.

The annulus 2a is bored at one end as shown at 20a for journaled sliding reception on the bearing-end 13a of the tool shank 10a, with the tool shank shouldered at 12a and having pins 14a projecting therefrom for reception in cooperating bores 15a in the end of the annulus 2a. A one-way clutch 16a, similar to that previously described, is provided between the bearing 13a and the bore 20a of the annulus 2a.

The opposite end of the annulus 2a is enlarged and forms a shouldered bore 21 adapted for detachable reception of an auxiliary annulus 22. The cutting-thread 1a is an interior thread in the bore of the annulus 22, the thread being arranged as previously described, i. e. it is fluted as shown at 3a, with respective ends of the thread

chamfered, and with cutting-edges and relieved-edges at respective sides of one end of each flute, in longitudinal alignment with relieved-edges and cutting-edges at respective sides of the opposite end of each flute. The annulus 22 is thus adapted for mounting in the bore 21 with either end of its thread 1a forming the leading end which is adapted for threaded engagement with the work; and when the annulus is thus mounted in its bore 21 for use of either end of its thread it may be detachably fixed against rotation and longitudinal displacement by a set screw 23.

The annulus 2a and the auxiliary annulus 22 are of relatively light metal such as an aluminum alloy, preferably with sleeves 25-26 fixed in the respective ends of the annulus 2a and forming the bores 20a-21. The sleeve 25 is preferably flanged at its outer end so as to overlie the end of the annulus 2a and form the surface of the annulus which is adapted to abut the shoulder 12a, and the sleeve 26 is preferably flanged at its inner end so as to abut the annulus 2a and form the shoulder of the bore 21 which is adapted for abutment by the inner end of the auxiliary annulus 22. The sleeves 25-26 may be fixed in their cooperating bores in any usual manner, preferably by shrinking them in place; and are of wear-resisting material, preferably a metal harder than the aluminum alloy annulus 2a-22.

The operation is the same as that previously described, the thread-cutting unit 2a-22 floating on its bearing 13a for thread-lead of this relatively light unit by its relative rotation and threaded engagement with the work, free of positive feed of the shank 10a which is employed merely for maintaining engagement of the pins 14a in their cooperating bores 15a during the thread cutting operation and for clearing the shoulder 12a of the annulus 2a during threaded retraction of the annulus from the work. While threading the work and during subsequent retraction of the die from the threaded work, the longitudinal pressure against the cut thread is therefore merely that resulting from thread-lead of the relatively light unit 2a-22, exclusive of the weight of the shank 10a, thereby threading the work without distorting the cut thread.

I claim:

1. In a threading tool, an annulus having a cutting-thread, longitudinal flutes defining arcuate lengths of the cutting-thread between circumferentially next adjacent flutes, and means for rotatably supporting the annulus, the annulus being adapted for reverse mounting relative to the supporting means for use of either end of the cutting-thread, the arcuate lengths of the cutting-thread having cutting-edges and relieved-edges at their respective ends, with the cutting-edges and the relieved-edges of those arcuate lengths of the cutting-thread which are between one end of the thread and medially of its length, circumferentially reversed with relation to the cutting-edges and the relieved-edges of those arcuate lengths of the cutting-thread which are between the opposite end of the thread and medially of its length.

2. In a threading tool, an annulus having a cutting-thread, a tool shank the external periphery of the shank and the internal periphery of the annulus forming cooperating bearing surfaces adapting the annulus for rotatable mounting on the shank with the annulus adapted for longitudinal displacement relative to the shank, means for fixing the annulus against rotation relative to the shank when relatively longitu-

dinarily displaced in one direction, said means permitting relative longitudinal displacement of the annulus in the opposite direction and adapted to release the annulus for rotation relative to the shank when the annulus is longitudinally displaced in said opposite direction, and a clutch comprising a groove in one of the cooperating bearing surfaces tapering in depth circumferentially of the annulus and shank, and a roller in said tapering groove for binding the annulus against rotation relative to the shank in one direction but releasing the annulus for rotation relative to the shank in the opposite direction, said clutch permitting longitudinal displacement of the annulus relative to the shank.

3. In a threading tool, a tool shank adapted for mounting of one end of the shank in a holder, an annulus of relatively light material and having a cutting-thread, the external periphery of the opposite end of the shank and the internal periphery of the annulus forming cooperating bearing surfaces adapting the annulus for rotatable mounting on said opposite end of the shank with the annulus adapted for longitudinal displacement relative to the shank, cooperating means between said opposite end of the shank and the annulus for fixing the annulus against rotation relative to the shank when relatively longitudinally displaced in one direction, said means permitting relative longitudinal displacement of the annulus in the opposite direction and adapted to release the annulus for rotation relative to the shank when the annulus is longitudinally displaced in said opposite direction, and a clutch comprising a groove in one of the cooperating bearing surfaces tapering in depth circumferentially of the annulus and shank, and a roller in said tapering groove for binding the annulus against rotation relative to the shank in one direction but releasing the annulus for rotation relative to the shank in the opposite direction, said clutch permitting longitudinal displacement of the annulus relative to the shank.

4. In a threading tool, a tool shank having a shouldered bearing-end, a pin projecting longitudinally from the shoulder, an annulus having a cutting-thread, the external periphery of the bearing-end of the shank and the internal periphery of the annulus forming cooperating bearing surfaces adapting the annulus for sliding journaled reception on the bearing-end of the shank, the annulus having a bore adapted for reception of the pin, and a clutch comprising a groove in one of the cooperating bearing surfaces tapering in depth circumferentially of the annulus and shank, and a roller in said tapering groove permitting longitudinal displacement of the annulus relative to the shank and fixing the annulus against rotation relative to the shank in one direction but automatically releasing the annulus for rotation relative to the shank in the opposite direction.

5. In a threading tool, a tool shank having a shouldered bearing-end, a pin projecting longitudinally from the shoulder, an annulus adapted for sliding journaled reception on the bearing-end of the shank with the annulus in either of axially reversed positions, a cutting-thread at the external periphery of the annulus adapted for thread-cutting by the respective ends of the thread when the annulus is in its respective axially reversed positions, each end of the annulus having a bore adapted for respective reception of the pin when the annulus is in its respective

5 axially reversed positions, a groove in the external periphery of the bearing-end of the shank tapering in depth circumferentially of the shank, and a roller in the tapering groove permitting longitudinal displacement of the annulus relative to the shank and fixing the annulus against rotation relative to the shank in one direction but automatically releasing the annulus for rotation relative to the shank in the opposite direction.

10 6. In a threading tool, an annulus having a cutting thread interrupted at circumferentially spaced points so as to define arcuate lengths of the cutting-thread between circumferentially next adjacent interruptions, the annulus being adapted for axially-reversible rotatable mounting for use of one end or the other of the cutting thread of the rotatable annulus, the arcuate lengths of the cutting-thread having cutting-edges and relieved-edges at their respective ends, with the cutting-edges and the relieved-edges of those arcuate lengths of the cutting-thread which are between one end of the thread and medially of its length, circumferentially reversed with relation to the cutting-edges and the relieved-edges 20 of those arcuate lengths of the cutting-thread which are between the opposite end of the thread and medially of its length.

25 7. In a threading tool, an annulus having a cutting-thread interrupted at circumferentially spaced points so as to define arcuate lengths of the cutting-thread between circumferentially next adjacent interruptions, the annulus being adapted for axially-reversible rotatable mounting for use of one end or the other of the cutting-thread of the rotatable annulus, the arcuate lengths of the cutting-thread having cutting-edges at one end, with the cutting-edges of those arcuate lengths of the cutting-thread which are between one end of the thread and medially of its length, circumferentially reversed with relation to the cutting-edges of those arcuate lengths of the cutting-thread which are between the opposite end of the thread and medially of its length.

30 8. In a threading tool, a tool shank, an annulus having a cutting-thread at its external periphery, the tool shank and the bore of the annulus comprising cooperating bearing surfaces adapting the annulus for rotatable and axially displaceable mounting on the tool shank, with the annulus in either of axially reversed positions for use of the portion of the cutting-thread which is adjacent respective ends of the annulus when the latter is in its respective axially reversed positions, means on the tool shank and the annulus, cooperating when the annulus is in either of its axially reversed positions, for fixing the annulus against rotation relative to the tool shank when said annulus is relatively axially displaced 35 in one direction, said means permitting relative axial displacement of the annulus in the opposite direction and being adapted for release responsive to said last mentioned relative axial displacement, and a clutch operable when the annulus is in either of its axially reversed positions, said clutch comprising a groove in the bearing surface of the tool shank tapering in depth circumferentially of the annulus, and a roller in said tapering groove binding the annulus against rotation relative to the tool shank in one direction but releasing the annulus for relative rotation in the opposite direction.

40 9. In a threading tool, a tool shank, an annulus having a cutting-thread at its external periphery, the tool shank and the bore of the

annulus comprising cooperating bearing surfaces adapting the annulus for rotatable and axially displaceable mounting on the tool shank, with the annulus in either of axially reversed positions for use of the portion of the cutting-thread which is adjacent respective ends of the annulus when the latter is in its respective axially reversed positions, means on the tool shank and the annulus, cooperating when the annulus is in either of its axially reversed positions, for fixing the annulus against rotation relative to the tool shank when said annulus is relatively axially displaced

5 in one direction, said means permitting relative axial displacement of the annulus in the opposite direction and being adapted for release responsive to said last mentioned relative axial displacement, and a clutch between the cooperating bearing surfaces and surrounded by the annulus when the latter is in either of its axially reversed positions, for binding the annulus against rotation relative to the tool shank in one direction but releasing the annulus for relative rotation in the opposite direction.

HARDING F. BAKEWELL.
